(57) **CLAIM**

We claim the ornamental design for a cutlery sheath, as shown and described.

DESCRIPTION

FIG. 1 is a perspective view of a cutlery sheath according to the new design;

FIG. 2 is a front view of the cutlery sheath shown in FIG. 1; FIG. 3 is a rear view of the cutlery sheath shown in FIG. 1; FIG. 4 is a right side view of the cutlery sheath shown in FIG. 1;

FIG. 5 is a left side view of the cutlery sheath shown in FIG. 1;

FIG. 6 is a top view of the cutlery sheath shown in FIG. 1; and, FIG. 7 is a bottom view of the cutlery sheath shown in FIG. 1. The broken lines shown in FIGS. 1-3 and 7 are included for the purpose of illustrating portions of the cutlery sheath that form no part of the claimed design.

1 Claim, 3 Drawing Sheets

FIG. 1
